(57) **CLAIM**

The ornamental design for a mini in-line ground fault circuit interrupter, as shown and described.

DESCRIPTION

FIG. 1 is a front, left perspective view of mini in-line ground fault circuit interrupter according to our new design;

FIG. 2 is rear, right perspective view of thereof;

FIG. 3 is front view thereof;

FIG. 4 is rear view thereof;

FIG. 5 is left view thereof;

FIG. 6 is a right view thereof;

FIG. 7 is a top view thereof with a seal provided over a top opening; and,

FIG. 8 is bottom view thereof.

The features shown in dash-dot broken lines form no part of the claimed design.
